UNITED STATES PATENT OFFICE.

JONATHAN A. HUNT, OF WESTBOROUGH, MASSACHUSETTS.

DESIGN FOR A SADDLE SPRING OR SUPPORT.

SPECIFICATION forming part of Design No. 28,479, dated April 12, 1898.

Application filed August 1, 1896. Serial No. 601,394. Term of patent 7 years.

To all whom it may concern:

Be it known that I, JONATHAN A. HUNT, a citizen of the United States, residing at Westborough, in the county of Worcester and State 5 of Massachusetts, have invented and produced a new and original Design for a Bicycle-Saddle Spring, of which the following is a specification, reference being had to the accompanying drawings, forming a part thereof.

10 My invention relates to a spring or support for bicycle-saddles, &c.; and my invention consists in the new and original design for a saddle spring or support, as will be hereinafter fully described.

15 Referring to the drawings, Figure 1 is a plan view of a spring, showing my design; and Fig. 2 is an edge view of the same, looking in the direction of arrow *a*, Fig. 1.

The bicycle-saddle spring or support is 20 formed from a single piece of rod or wire, which is bent into the shape shown in Fig. 1. The central portion *b* is straight its entire length, and the rod or wire at each end of

this central portion is bent so as to form the eyes or curves *c*. From these eyes or curves 25 the ends *a* extend parallel any suitable distance to the point *d*, and from the point *d* to the parts *e* the ends converge inwardly toward each other and from the point *e* they extend parallel outwardly. 30

This spring or support is curved downwardly between its ends, as shown in Fig. 2, and the curve is an even one from end to end.

The essential features of my invention consist in the spring or support curved from one 35 end to the other and having its two free ends first to converge toward each other and then extend parallel.

Having thus described my invention, I claim—

40 A design for a saddle spring or support, substantially as herein shown and described.

J. A. HUNT.
